UNITED STATES PATENT OFFICE.

EDWARD G. CARR, OF OAKLAND, CALIFORNIA.

APPARATUS FOR COMPACTING CONCRETE.

Application filed October 8, 1917. Serial No. 195,473.

To all whom it may concern:

Be it known that I, EDWARD G. CARR, a citizen of the United States, residing at Oakland, in the county of Alameda and State of California, have invented new and useful Improvements in Apparatus for Compacting Concrete, of which the following is a specification.

This invention relates to the preparation of mixtures, such as concrete, for solidification, by compactly arranging the solid particles in the mass, and is especially applicable to the manufacturing of concrete roadways. This is accomplished by bringing the particles of moisture and air to the surface of the mass and shifting the solid particles within it so that they lie more compactly together, with the advantages hereinafter set forth.

It has been the practice heretofore to seek this result by merely tamping concrete, that is, exerting pressure upon it, thereby jamming the pieces of rock in the mass into somewhat closer relationship and forcing a small part of the contained moisture and air out around the edges of the tamper. This method was improved and made applicable in a practical manner to concrete roadways in Patent No. 1,203,482, issued to me October 31st, 1916, wherein an apparatus was provided for speeding up the successive blows of the tamper, accomplishing more work in a given interval of time and to a greater degree improving the quality of that work. It did not, however, remove particles of air by means of suction and became less effective as the amount of free moisture in the mass was reduced.

The present invention lies in the process of and apparatus for employing suction to compact a mass of concrete in plastic condition by withdrawing a solid surface (which may or may not have been applied to the concrete in a forcible manner) so quickly and suddenly as to create a suction or partial vacuum between that surface and the mass to be compacted. Such a suction creates a disturbance or agitation in the mass, opposite in direction from that produced by pressure exerted thereupon, and a pressure within the mass acting in direction toward its surface, this latter pressure acting to force the moisture out of the concrete, to cause air particles to expand and burst their way out to the surface, and to agitate its component particles. In other words, by

this invention moisture is sucked and air caused to blow itself out of the mass, whereas prior hereto the method has been to squeeze them out if at all.

When a thrust pressure is applied alternately with suction, agitation within the mass in two relatively opposite directions is produced which causes the individual solid particles in the concrete to shift with relation to each other, whereas the most enlightened method heretofore known has been merely to agitate the mass as a whole, if at all, and in one direction only. Since the movement, due to suction, tends to agitate the mass and its particles in a direction opposite to that of a struck blow thereon, when this suction is introduced between the striking of blows upon the mass, the rock or other solid particles are prevented from jamming across one another and are caused to be arranged more compactly. Rocks will jam just like logs and a steady or intermittent pressure or pounding of the mass in the same direction will not disengage them to any appreciable extent. But when, being jammed, the particles in the mass are agitated by a force acting in a direction opposite to that of an imposed pressure upon the mass the keystone of the rocks which have jammed into an arch, as it were, will be upset and the rocks will tumble into closer union.

In addition to this agitation, the creation of a vacuum permits the air particles in the mass, which are under atmospheric or greater pressure, to exercise relatively greater force against the containing walls of solid matter and thus literally to explode their way to the surface. In a so-called "dry" mixture there has heretofore been no effective method of removing this air.

Referring now to the drawings:

Fig. 1 is a side elevation of the apparatus by which the method of compacting concrete is practiced.

Fig. 2 is a plan view of the apparatus shown in Fig. 1.

Fig. 3 is a cross section of the vacuum-producing member of said apparatus at the commencement of its upward or vacuum-producing stroke.

Fig. 4 is a cross section of the vacuum-producing member of said apparatus at the conclusion of its upward or vacuum-producing stroke.

The apparatus used by me in practicing

this process, which is particularly designed for its use in the manufacture of highways, is in its source of power, means of locomotion and frame similar to the device disclosed in United States Letters Patent No. 1,204,245, heretofore granted to me. But whereas in that patent, means is disclosed for applying a varying or intermittent pressure upon the surface of the concrete 10 through a tamping bar flexibly connected to the frame and held at the said surface there is no suction produced or provided for.

In the structure now disclosed there is a bar 6 which is shod with a channel iron 7 to 15 keep the corners thereof from wearing and destroying the vacuum-producing surface. Said bar 6 is suspended at either end across the surface to be compacted by laminated springs 2 which hold the bar 6 an appreciable distance above the level of the surface 10 to be compacted, in the device shown this distance being at least two inches.

These springs 2 are fastened to the frame 11 at one end by a bracket 12 and at the 25 other end by a shackle 13. Power is supplied from a motor at 14 and conveyed to a shaft 15 which actuates the wheels 16 of the frame through the wheels 17 and a belt 18, causing it to travel. Power is also 30 transmitted to shafts 19-19' and thence through a universal joint 20 to an unbalanced weight 21.

The tendency of the weight 21 to rotate 35 out of its center of mass by centrifugal force causes shaft 19' to have an up and down movement. This movement causes the bar 6 to move downwardly against the springs 2 and thrust against the surface to be compacted. It will force its way a 40 slight distance into the mass, as shown in Fig. 3. The springs 2 are distorted downwardly so that at the instant the downward stroke is completed the bar 6 is quickly jerked back up to the level of the bar when 45 at rest and several inches above the surface to be compacted. This sudden lift creates a partial vacuum or suction which causes the bubbles of air in the mass to expand and blow out, the particles of rock to shift with 50 relation to each other and break up any existing jams, and sucks out the moisture.

The frame is, during the operation, slowly moved along the highway, the concrete of which is to be compacted, through 55 the motion of the wheels 16 at a speed of travel very much less for the interval of time employed in one vacuum production than is the width of the bar 6, so that the successive areas covered by the bar 6 overlap, thereby ensuring a smooth surface and thorough and even compacting.

While the benefits of the invention are secured irrespective of the speed at which the successive strokes and sudden lifts take place, the best results are obtainable if each

individual movement of alternate strokes and uplift comes before the agitation, produced in the mass by the preceding movement, has ceased. Rapid applications of pressure, so-called vibrations, were heretofore employed by me as a means of agitating a mass of concrete as a whole, but the agitation was thereby produced by a pressure or thrust in one direction only and therefore called for down strokes of the bar 75 6 just twice as rapid as are necessary in my new process and apparatus, since the new one produces a force in two directions for each cycle from one down stroke to another and thus produces twice as many agitations 80 for the same speed of operation.

Other advantages are that by this process the proportion of rock in the concrete can be greatly increased, with a corresponding saving of cement or other binding 85 means, which is the expensive element, this being occasioned by the greater compacting of the rock; a mixture can be compacted by this method which is drier than a mixture which can be tamped, so that there is less 90 water to be removed and less possible porosity; and a concrete of superior hardness and solidity is formed, since the air is removed therefrom and in addition moisture, both of which, when the concrete has 95 solidified, tend to make it porous and to disintegrate.

The word suction is used in this specification and in the claim in its ordinary and commonly accepted significance. Looking 100 at Fig. 4 of the drawings, the concrete which is shown lifted up is, of course, elevated by the pressure of the air on the adjacent surfaces of the concrete. When the bar 6 is raised suddenly or quickly, when in contact 105 with the concrete, the air pressure on the top of the concrete adjacent the bar is exerted through the mass of the concrete to fill the vacuum created by the bar in its ascent. The air is pressing upon the concrete with a force of about fifteen pounds 110 per square inch. Taking into account on a road fourteen feet wide a strip across the road adjacent one side of the bar and extending only one inch in the length of the 115 road, the air pressure exerted upon this strip will be over a ton and a quarter, figuring the pressure at fifteen pounds per square inch. The pressure exerted by the air is that of a fluid under pressure and the pressure is 120 transmitted through the plastic part of the concrete mass tending to lift the concrete under the bar as the bar rises. The pieces of crushed rock, which form part of the concrete mass, under the bar are freely 125 moved by the upflowing plastic part of the concrete as there is no resistance to be overcome, apart from inertia, and any bridges or arches which these pieces of crushed rock have formed are destroyed. The plastic 130

part of the concrete moves and rises and falls in the same manner as liquid and plastic masses and its effect in producing motion of the pieces of crushed rock bodily depends upon the viscosity of the plastic mass, its velocity of movement and the cross-sectional areas of the pieces of rock in the direction of flow. But for all practical purposes in connection with this invention, the real advantage is the upward movement of the plastic mass between the crushed rock and the re-settling of the crushed rock. A downward pressure upon a mass of concrete, when the plastic part of the concrete can be displaced, usually results in forming bridges or arches with pieces of the rock which prevent further compacting. By moving the concrete mass up and down a shaking of the mass is produced which results in a more complete and closer assemblage of the pieces of crushed rock which are ordinarily used to constitute part of the concrete mass. The sand used in concrete is not ordinarily graded to a uniform size and the up and down movement of the concrete mass tends to move the sand particles and sift the smaller pieces into spaces which are too small for the larger pieces.

The springs 2 are means for giving a

bar 6 a quick, upward movement but the invention is not confined to the use of springs for this purpose, the only thing necessary being that the bar 6 be given a quick, powerful lift so that the pressure of the air adjacent the bar will lift the concrete under the bar.

Having thus described my invention, what I claim and desire to secure by Letters Patent is—

An apparatus for tamping concrete roadways in the course of manufacture, comprising a carriage, a vertically reciprocating tamping bar carried thereby, laminated springs for suspending said tamping bar from the carriage, and means for moving the tamping bar downwardly into engagement with the surface of the concrete mass, said springs acting to lift the tamping bar with such suddenness as to cause a suction to be applied thereby to the surface of the mass. 50

In testimony whereof I have hereunto set my hand in the presence of two subscribing witnesses.
